(57) CLAIM

The ornamental design of a cover for a cooler, as shown and described.

DESCRIPTION

Cross-reference is made to U.S. Design patent application Ser. No. 29/711,905, titled "Cover for a Cooler," filed on Nov. 4, 2019, which is expressly incorporated herein by reference.

FIG. 1 is an upper perspective view of a cover for a cooler; FIG. 2 is a front view of the design of FIG. 1; FIG. 3 is a rear view of the design of FIG. 1; FIG. 4 is a first side view of the design of FIG. 1; FIG. 5 is a second side view of the design of FIG. 1; FIG. 6 is a top view of the design of FIG. 1; FIG. 7 is a bottom view of the design of FIG. 1; and, FIG. 8 is a lower perspective view of the design of FIG. 1. The broken lines shown in the drawings are included for the purpose of illustrating the unclaimed boundary and/or unclaimed portions of a cover for a cooler. The broken lines form no part of the claimed design.
